UNITED STATES PATENT OFFICE.

JAMES LAKE, JR., OF NEW YORK, N. Y.

HAT-PRESSING MACHINE.

1,177,341.

Specification of Letters Patent. Patented Mar. 28, 1916.

Application filed August 11, 1915. Serial No. 44,959.

To all whom it may concern:

Be it known that I, JAMES LAKE, Jr., a citizen of the United States, and a resident of the city of New York, borough of Brooklyn, in the county of Kings and State of New York, have invented a new and Improved Hat-Pressing Machine, of which the following is a full, clear, and exact description.

10 Among the principal objects which the present invention has in view are: to provide a machine as characterized having a variable mold and adjustable operating mechanism therefor; to provide means for 15 augmenting the pressure exerted by a machine of the character mentioned; to provide adjustable means for locking the machine in operative position, and adjustable devices connected therewith for rendering 20 the lock sensitized to distribute the pressure applied to the machine.

Drawings.—Figure 1 is a front elevation of a machine constructed and arranged in accordance with the present invention; Fig. 2 is a side view of the same; Fig. 3 is a vertical section, taken as on the line 3—3 in Fig. 1, the machine being shown in the inoperative or open position; Fig. 4 is a similar view, the machine being shown in the closed or operating position; Fig. 5 is a detail view on an enlarged scale, showing a fragment of the pressure shaft and an eccentric cam mounted thereon, together with the end of a pull link operatively connected therewith; Fig. 6 is a detail view in perspective of the articulated links with which the machine is provided; Fig. 7 is a detail view on an enlarged scale, showing the cam shaft for increasing the pressure on the setting 40 frame; Fig. 8 is a detail view in perspective, showing a distributor bar with which the machine is provided; Fig. 9 is a detail view in perspective, showing a hat crown mold constructed and arranged in accordance 45 with the present invention; and Fig. 10 is a detail view in perspective, showing a complementary section for said mold.

The present invention has particular relation to hat pressing machines such as disclosed in Letters Patent of the United States, granted to me under date of January 26, 1915, numbered 1,126,492, to which patent reference is here made.

Description.—As seen in the drawings, 55 the herein disclosed machine has a cup-shaped crown mold 15, a hydraulic head 16

for filling the same and for exerting expansive pressure therein, a male brim die 17 and a female brim die 18. The mold 15 and die 17 are both removably disposed on a stationary steam heated table 19. The die 18 is permanently attached to a movable steam heated table 20. The head 16 is preferably constructed of rubber or other extensible material and is suspended from a closure 60 plate 21. The closure plate 21 is operatively connected with a feed screw 22, which is operatively engaged by a nut 23 to be elevated and depressed. A hand wheel 24 is connected with the nut 23 to facilitate the 65 manipulation of the said nut. The hand wheel 24 is held firmly in position by a retaining nut 25. The screw 22 is tubular forming a conduit for the passage of water from a supply pipe 26 to the interior of the head 70 75 16. It will be understood that the supply of water furnished by the pipe 16 is manually controlled and is under suitable pressure. It will also be understood that the tables 19 and 20 are hollowed to receive steam supplied for heating the said tables to the necessary or desired degree. The table 19 is cupped to form a chamber 27 wherein rests the mold 15 to be guided thereby. The mold 15 is supported by a heated tip 28, which 80 like the tables 19 and 20 is hollowed for heating by steam admitted thereto. The table 19 has a lower open-sided extension 29, in which is housed a tubular adjusting nut 30. The nut 30 operatively engages a screw 85 threaded plunger 31 to elevate and lower the same. The plunger 31 has a head 32 perforated to receive the pins 33 for pivotally supporting the tip 28 and mold 15 resting thereon.

The nut 30 is freely accessible, entrance being gained thereto from the open sides of the housing 29. The nut is furnished with a series of spanner holes 34, by which the nut may be turned to adjust the tip 28 and mold 15 to the desired operating position. The nut 30 is closed at the lower end by a screw cap 35, which is centrally perforated to pass the shank of a connecting screw 36, the head 37 whereof rests 90 within the nut 30, the inner wall whereof is rabbeted adjacent the lower edge to form an annular shoulder or rest for the head 37.

The screw 36 and the head 37 thereof are freely movable in the cap 35 and nut 30. 110 The screw is fixedly mounted in a collar 38. The collar 38 fits the eccentric 39 on the

shaft 40 to be raised and lowered thereby, for moving the crown mold 15 after the setting pressure has been applied to the dies 17 and 18 and between the head 16 and the wall of the mold 15, as hereinafter explained. For manipulating the shaft 40, a lever 41 is fixed thereto, said lever being disposed in a horizontal extension when the parts of the mold are separated, as seen best in Fig. 1 of the drawings. The extent of the lift of the mold 15 and tip 28 is dependent on the throw of the eccentric 39.

The head 16 and table 20 by which the same is supported, is lowered and raised by a distributor bar 42. The bar 42 as seen best in Fig. 8 of the drawings, is furnished at the opposite ends with brackets 43, for supporting at the upper ends thereof, collars 44. The collars 44 receive the connecting rods 45, which at the upper end have threaded extensions 46 held in adjusted relation by the nuts 47 that bear on both sides of bracket extensions 48 set out from the table 20.

The setting pressure for the dies 17 and 18 is obtained by rocking the shaft 49. The shaft 49 is mounted in bearings 50 formed in the extensions 43 of the bar 42. Fixedly mounted on the shaft 49 are heavy eccentrics 51 disposed, as seen best in Fig. 1 of the drawings, in juxtaposed relation to the extensions 43. The eccentrics 51 rotate within the collars 52 formed at the ends of the arms 53, which are connected as a rigid structure by a brace 54. The upper ends of the arms 53 are yoked to form divided hinge knuckles 55, the ends whereof are perforated to receive the pins 56 when the same are passed through corresponding perforations formed in the arms 57. The arms 57 are rigidly connected by a brace 58. The arms 53 and 57 are so connected by the pins 56 that in service, the center of the said pins and the center of the collars 52 and the bearings 59 at the upper ends of the arms 57 are slightly out of line, the said pins thereof passing the plane with which the centers of the said collars and bearings are coincident. To regulate the distance to which the pins pass the said plane, there are provided the set screws 60. The screws 60 are each mounted in threaded perforations tapped in the outer end of offsets 61. The offsets 61 have a flat surface 55 to register with a corresponding surface on offsets 62 formed on the arm 63. The ends of the screws 60 bear against the surface of the offsets 62 and by preventing the too close abutment of the offsets 61 and 62, regulate the swing of the arms 53 and 57 to and past the vertical plane.

The arms 57 are united with webs 64, pins 65 passing through said webs and the bearings 59 in the arms 57, as shown best in Fig. 1 of the drawings. The webs 64 are

integrally formed with the frame table 66.

From the foregoing, it will be seen that when the arms 53 and 57 have been straightened, a thrust is exerted therethrough by the eccentrics 51, when the shaft 59 is rocked. Through the shaft 49, pressure is exerted to the distributor bar 42 to lower the same and thereby through the medium of the rods 45, forces the die 18 on the die 17. To rock the shaft 49, a long lever 67 is employed. This lever is seen best in Figs. 1 and 2 of the drawings. The multiplication of the force exerted by the eccentrics on the shaft 49 is sufficiently great to set the brim of a hat between the dies 17 and 18.

The distributor bar 42 is lowered in the manner above set forth by depressing the foot lever 68. The lever 68 is pivoted on a shaft 69. The bar 42 and parts connected therewith are normally held in the position shown in Figs. 2 and 3 of the drawings, by the counterbalancing weight 70. The wedge 70 is slidably mounted on the rod 71, which is held by a set screw 72 in a socket member 73. The socket member 73 is formed at the rear end of a rocking arm 74. The arm 74 and member 73 formed therewith, are both supported by a pivot shaft 75. The arm 74 is flexibly connected with the bar 42 by links 76. The links 76 are united by pins 77 with lugs 78 on the bottom of the bar 42, as seen best in Figs. 3 and 8 of the drawings. To assist in supporting the weight of the bar 42 and members supported thereby, the coil springs 79 are connected to a shaft 80. As seen in Fig. 1, a battery of springs 79 is employed. These may be increased or reduced in number according as the work required thereof demands. The weight 70 is shifted on the rod 71 to modify the action of the arm 74 by assisting the springs 79. The weight 70 is adjusted on the rod 71 and held in fixed relation thereon by a set screw 81.

The lever 67 is operatively connected with the arm 74 by bowed links 82, said links being connected with a lug 83, by means of a pin 84. The connection between the lever 67 and the links 82 is made by a pin 85, as seen best in Figs. 1 and 3 of the drawings.

To lock the lever 68 in depressed or service position, a cone nut 86 is provided, said nut having a tapped perforation to receive a screw threaded section 87 of a guide rod 88. When the foot lever 67 is depressed, it swings under the nut 86 to be held thereby in its depressed position, until manually released at the end of the pressing operation of the machine.

The crown mold 15 is placed loosely in the chamber 27 to rest on the tip 28. To hold the said mold in register with the die 17, the latter is provided with a series of

pins 89. To receive the pins 89, there is formed a series of holes 90 in the rim wall of the said mold 15. The holes 90 are deep enough to permit the mold 15 to move freely 5 to and from the overhanging edge 91 of the brim die 17. The pins 89 also serve to hold the supplementary mold section 92. The section 92 is provided with perforations 93, through which the said pins extend 10 when the section 92 is assembled with the mold 15.

Operation.—Having a machine constructed and arranged as shown in the drawings and described, the operation is as follows: 15 The hat shape having been adjusted to the block mold 15 and the brim die 17, the operator places his foot on the lever 68 and depresses the free end thereof until the same swings below the nut 86. With the 20 swing of the lever 68, the arm 74 is rocked to depress the bar 42 and parts connected therewith. At the lower extremity of the movement of the lever 68 and the bar 42, the head 16 enters fully into the mold 15 25 and the die 18 is brought to rest firmly on the die 17. In this position of the bar 42, the arms 53 and 57 are disposed as shown in Figs. 4 and 6, and the springs 79 have been fully extended, while the weight 70 is 30 lifted to the position shown in Fig. 4 of the drawings. The straightening of the arms 53 causes the same to impinge on the bracket 94, which as shown in Fig. 7 of the drawings, is clamped to the shaft 49. This engagement rocks the shaft 49, to throw the lever 67 forward convenient to the hand of the operator. The lever 67 is now depressed until the handle end thereof rests on the floor or on a fixture provided there- 35 for. The partial rotation thus imparted to the shaft 49 rotates the eccentrics 51 in the collars 52. The collars 52 being held rigidly by the arms 53 and 57 and the webs 64, the shaft 49 and bar 42 connected ther- 40 with are depressed to exert through the rods 45, a full compression of the dies 17 and 18 on the hat shape and the brim there- 45 of, held therebetween. The levers 68 and 67 being thus disposed and the hat brim 50 being pressed to shape, the operator by manipulating the valve 95, shown in Fig. 4 on the pipe 26, permits water to flow into the head 16 until the reading on a pressure 55 gage 96 indicates the desired pressure exerted through the head 16 on the crown or the hat in the block mold 15.

In the normal operation of the machine, the block mold 15 is held away from the overhanging edge 91 of the die 17, as shown best in Fig. 3 of the drawings. This space is not taken up or contracted until the pressure is introduced through the head 16 on the hat crown and until the operations above described, have been performed. The hydraulic pressure having been applied

through the head 16, the operator now lifts the lever 41 to an upright position, rocking the shaft 40 and the eccentric 39 thereon within the collar 38 to lift the same and the nut 30 supported thereby within the housing 70 29. As mentioned, the tip 28 supports the block mold 15 and is adjusted by the screw 31. The block mold 15 is by this action moved up to close the gap between the overhanging edge 91 and the edge wall of the 75 mold 15. In this manner, the crown of the hat is formed and set to any desired height independently of the brim dies 17 and 18. The fullness at the side of the crown is also taken up at that portion of the crown which 80 is usually covered by the hat band.

If it is desired to increase the height of the crown, this is accomplished by inserting one or more sections, such as indicated by the numeral 92 in Fig. 3 of the drawings. 85 When the sections 92 are employed, the nut 30 is manipulated to correspondingly lower the mold 15. Thus, if the block mold 15 is shaped to form a Fedora crown, the said crown may be increased or diminished in 90 height by adding one or more of the sections 92. Care is, however, taken that in all instances, the space between the upper edge of the mold 15 and the overhanging edge 91 of the die 17, is the same and corre- 95 sponds to the thrust of the eccentric 39, when the shaft 40 is rocked. It is obvious that having the brim dies 17 and 18, the shape of the crown may be infinitely and quickly varied by substituting other block 100 molds, such as 15, or by adding or subtracting filling sections, such as those indicated by the numeral 92.

After the pressure has been maintained on the hat sufficiently long to set the material, 105 the press is unlocked by first relieving the water pressure on the head 16 and then by moving the lever 41 to the horizontal position and then by lifting the lever 67 until the bracket 94 engages the arm 53. A further pressure on the lever 67 accompanied by a lateral movement of the lever 68 to disengage the same from the nut 86, throws the arms 53 from the vertical position to move the pivot pins 67 out of line. This 110 permits the springs 79 and the weight 70 to rock the arm 74 for moving the bar 42 and parts connected therewith, including the brim die 18 and the head 16 to the position shown in Fig. 1 of the drawings. 115 The machine is thus brought back to the open or inactive position, shown in Figs. 1 to 3 of the drawings.

Claims:—

1. A machine as characterized comprising 125 a crown mold; a brim die having a central opening providing an edge overhanging said crown mold and shaped to correspond therewith; means for holding said mold and die in register; means for normally holding 130

- said mold in spaced relation to said overhanging edge; and supplementary sections for mounting on said mold for varying the combined depth thereof.
- 5 2. A machine as characterized comprising a crown mold; a brim die having a central opening providing an edge overhanging said crown mold and shaped to correspond therewith; means for holding said mold and die 10 in register; means for normally holding said mold in spaced relation to said overhanging edge; supplementary sections for mounting on said mold for varying the combined depth thereof; and means for adjusting the spaced 15 relation between said edge and said mold.
3. A machine as characterized comprising a stationary brim die; a supporting frame therefor, embodying a table having a centrally disposed hollow chamber; a movable 20 brim die normally suspended in superposed relation to said stationary brim die; a suspension frame for said movable die embodying a distributor bar extending across said frame below said table and laterally disposed connecting rods operatively uniting 25 said distributor bar and supports for said movable die; a reciprocating mechanism for said distributor bar embodying a plurality of pivotally connected frames, each frame 30 having straight legs in separate relation, the legs of one of the pivoted frames being pivotally connected with said supporting frame, the other of said frames being pivotally connected with said distributor bar, and 35 both of said frames being pivotally connected each with the other; means for moving the pivotal connection between said frames beyond the plane coincident with the centers of the pivotal connection of said 40 frames with said supporting frame and said distributor bar; and means for regulating the extent of the movement of said pivotal connection beyond said plane.
4. A machine as characterized comprising 45 a stationary brim die; a supporting frame therefor, embodying a table having a centrally disposed hollow chamber; a movable brim die normally suspended in superposed relation to said stationary brim die; a suspension frame for said movable die embodying a distributor bar extending across said frame below said table and laterally disposed connecting rods operatively uniting 50 said distributor bar and supports for said movable die; a reciprocating mechanism for said distributor bar embodying a plurality of pivotally connected frames, each frame 55 having straight legs in separate relation, the legs of one of the pivoted frames being pivotally connected with said supporting frame, the other of said frames being pivotally connected with said distributor bar, and both of said frames being pivotally connected each with the other; means for moving the pivotal connection between said frames beyond the plane coincident with the centers of the pivotal connection of said 60 frames with said supporting frame and said distributor bar; and both of said frames being pivotally connected each with the other; means for arresting the movement of said legs; and a plurality of adjustable devices for disposal between said extensions for regulating the relative movement of said frames.

connected each with the other; means for moving the pivotal connection between said frames beyond the plane coincident with the centers of the pivotal connection of said frames with said supporting frame and said distributor bar; and a plurality of extensions set out from said legs for arresting the movement of said legs.

5. A machine as characterized comprising a stationary brim die; a supporting frame therefor, embodying a table having a centrally disposed hollow chamber; a movable brim die normally suspended in superposed relation to said stationary brim die; a suspension frame for said movable die embodying a distributor bar extending across said frame below said table and laterally disposed connecting rods operatively uniting said distributor bar and supports for said movable die; a reciprocating mechanism for said distributor bar embodying a plurality of pivotally connected frames, each frame 80 having straight legs in separate relation, the legs of one of the pivoted frames being pivotally connected with said supporting frame, the other of said frames being pivotally connected with said distributor bar, and both of said frames being pivotally connected each with the other; means for moving the pivotal connection between said frames beyond the plane coincident with the centers of the pivotal connection of said 85 frames with said supporting frame and said distributor bar; a plurality of extensions set out from said legs for arresting the movement of said legs; and a plurality of 90 adjustable devices for disposal between said extensions for regulating the relative movement of said frames.

6. A machine as characterized embodying a fixed die and a movable die; a stationary frame; a setting mechanism for disposing said movable die on said fixed die, said mechanism embodying a plurality of pivotally connected frames adapted for swinging past a plane coincident with the pivotal connections of said frames for locking the 110 same in extended position; and a power lever operatively connected with the lower of said frames at the lower end thereof, said lever embodying a bracket for engaging one of said frames when said lever is moved to its 115 releasing position, said bracket operating to move said frames and the united ends thereof to the opposite side of said plane coincident with the pivotal connections of said frames.

In witness whereof I have signed my 120 name to this specification in the presence of two subscribing witnesses.
